FOUNDRY MOLDING BOX

Application filed April 6, 1929, Serial No. 353,080, and in Great Britain April 16, 1928.

This invention relates to improvements in molding boxes and the like and refers particularly to molding boxes, core boxes, metallic molds for die-casting and the like of the type in which a number of boxes or molds 5 may be required to be superimposed and accurately located and secured together to form a complete mold.

In foundry work, it is a common practice to 10 assemble a number of such boxes and locate them relatively to each other by a number of separate and, in many cases, staggered connections or location devices. This is commonly done by means of pins rigidly attached to one part engaging holes or lugs on 15 an adjacent part or by means of loose pins engaging holes or lugs or adjacent parts. In some cases the pins and holes are cylindrical; in others they are V-shaped; but in any case 20 the connection is duplicated between each of the several boxes in one complete mold. It will therefore be obvious, as there must be a small amount of play between each attachment pin and the lugs or holes with which it 25 is engaged, that in a deep casting, molded in a number of boxes, there must be a cumulative error of quite serious proportions. This error must be allowed for in the casting; and on a machined section on a casting may necessi- 30 tate correspondingly greater labour in machining and losses in metal on the finished work while on an unmachined section on a casting allowance must be made for possible inaccuracies when calculating the thickness 35 or other dimensions.

With location or connection means which function only between adjacent boxes, or a pair of boxes, it is difficult to maintain an accurate fit of an attachment pin and the box 40 lugs, for the reason that the parallelism of the bores of the lugs cannot be either commercially produced or maintained for these purposes in their strict right-angle relationship to the plane of the box-part. Accordingly, 45 clearances have to be allowed, and if such clearances as are generally employed are reduced, then, owing to the entry of dust and fine grains of sand which are trapped between the working surfaces of the pin and hole, ex- 50 cessive binding is caused in assembly and use

under actual foundry conditions. The forcing of a pin in such cases rolls the abrasive grains down the metal faces and scores the pin and the bore and wear rapidly occurs.

Obviously, therefore, the location of a 55 number of boxes presents considerable difficulty when accuracy is desirable and the usual and known methods of location are employed.

It is an object of our invention to enable 60 common attachment and locating members to be employed with a range of several boxes and to render each box quite standard as to its lugs and attachment means so that not only is a coaxial location of the various boxes 65 possible, but also a complete interchangeability of all boxes comprising a range or set is obtained. Another object is to accomplish this in such a manner that, although 70 the tolerance between the common member and the lug of any individual box is smaller than hitherto, there is no difficulty in assembling the boxes in superposed relation and accuracy is maintained over a long period of 75 use.

In accordance with our invention, the 80 boxes are provided at a fixed point, which is the same in all and is preferably on an axial diameter, with the usual lugs, or an aperture in a flange serving the same purpose, and the 85 bores in the lugs, or the apertures in the flange, are mere clearances formed larger than the pin member on which the boxes are to fit, and thereupon are adjustably secured knife edged or nose-edged location plates 90 which can be set with accuracy to accommodate the locating pin member.

These location plates at one side of the box are each V shaped to give a four point contact 95 each of line depth only on the pin member, while at the other side two parallel edged strips directed parallel with the axis of the box which passes through the lugs, and spaced to give a line contact on two opposite sides of the pin, will suffice.

The combination of these location plates having knife or nose edged contact lines with an accurately made and gauged, hard, cylindrical pin common to all the box parts is a useful, practical embodiment ensuring greater 100

accuracy of work and economy in labour and metal.

These improved location devices are automatically self-clearing, as sand grains cannot be trapped between the pin and these line contact location plates; there is no binding therefore, a much closer fitting pin can be worked easily and smoothly, wear is reduced and great accuracy is permitted and maintained.

We make use of two sets of location plates on each box, one set near the top and one set near the bottom. This ensures that the box surface and the axes of the pins are held truly at right angles to each other. While it is not essential to make this provision on each end of each box part of a pair or set of boxes, when working on flat or hollow surfaced molds, it is always necessary with one of such parts, and therefore in commercial use we prefer to make it a standard practice. In the accompanying drawings:

Figure 1 is a perspective view of a box.

Figure 2, is a central longitudinal section thereof on a larger scale.

Figure 3, is a plan of one part of the location plates which are shown at the left hand end of Figure 1.

Figure 4, is a plan of one of the plates shown at the right hand end of Figure 1.

Figure 5, is a section on line 5—5 of Figure 3 or Figure 4.

In this illustrated example we form each box with two lugs *a* at each end, one near the top and the other near the bottom, opposing lugs at the two ends being in the same planes. In each lug is a clearance aperture *b* large enough to pass freely the pins on which all the boxes are to work. On the faces of the lugs *a* which are remote from each other, we secure at one end two pairs of location plates *c* Figure 3, and at the other end two pairs of plates *d* Figure 4. The plates *c* are each V-shaped in their ends and they are assembled with their V ends opposite each other, but separated sufficiently for the four inclined lines thus produced to fit the cylindrical locating pins, which are to be used with them, with the smallest working clearance. We find in our own foundry practice this clearance may be reduced to 0.0005 (five ten-thousandths) of an inch on a pin of 1" diameter. Each angular edge *e* of these V-shaped ends is formed in the manner shown in Figure 5.

The lugs *a* at the other end of the box are similarly provided with pairs of location plates *d* each of which has an edge *f*, of section corresponding to Figure 5, along one end. These "knife edged" ends *f* are assembled opposite each other, separated sufficiently to fit a cylindrical pin at two opposite points only under the same conditions of accuracy at these points as in the case of the plates *c*. The holes in the lugs for the reception of the attachment bolts *g* for the location

plates *c* and *d* are extended lengthwise of the lug to form slots to permit adjustment of the plates when they are being set accurately on a suitable jig. In some cases, where steel boxes and plates are used, it may be convenient, instead of using bolts or like means for securing the location plates on the lugs, to spot-weld them when they have been located correctly in a setting up jig.

It will be obvious that the four edges *e* of the plates *c* and the two edges *f* of the plates *d* must be set in the same relative position in each box if all the boxes of a set are to be interchangeable and capable of use on a true cylindrical pin at each end common to all the box parts. For the setting of these plates any suitable jig giving this result can be employed as will be clear to those skilled in the art. A jig having master pins set for the various sizes of boxes is a convenient method, the pins being gauged to a size larger than the actual pins on which the boxes are to work by the extent of the clearance allowed.

It is preferred, but is not essential, to cast the location plates *c* and *d* and form the edges *e* as dead hard edges by the use of chills.

The pins for use with the box part illustrated in the drawings are not shown as these are merely true cylindrical pins, preferably hardened steel of a length to accommodate any required number of boxes in superposition.

We claim:

1. Foundry molding box or flask comprising in combination a frame part, lugs on opposite ends of said frame part, clearance apertures in the lugs, location means adjustably secured on said lugs to locate the frame parts at each end on a cylindrical location pin passed through said clearance apertures, said location means giving point contact on said pin, said location means at one end of said frame consisting of opposed plates having V notches in their opposite edges and at the other end of said frame consisting of similar plates with straight opposite edges.

2. Foundry molding box or flask comprising in combination a frame part, a pair of lugs on each of two opposite ends thereof, clearance holes in said lugs and knife-edged location plates adjustably secured on said lugs with their knife edges overlying said clearance apertures to locate the frame part at each end of a cylindrical location pin passed through said clearance apertures, said location plates at one end of said frame having V-notches in their opposite edges and at the other end of said frame having straight opposite edges.

3. In foundry molding boxes or flasks of the kind in which a rectangular box like molding part is provided at opposite ends with perforated lugs which cooperate with cylindrical pins common to a plurality of the

boxes to locate the boxes in proper molding relation one with another, the combination with said lugs of apertures which are clearances on the cylindrical pins with which the 5 lugs are to cooperate in locating said boxes, plates adjustably secured on the lugs at each end of the box with the ends of the plates opposing each other and overlying the clearance apertures, said overlying opposed ends 10 of said plates being formed with edges giving point contact on the cylindrical pins, and said plates at one end of said box part having V notches in their opposing edges the sides of which notches are knife edges, and said 15 plates at the other end of said box part having straight opposed edges longitudinally directed, said straight edges being formed as knife edges.

In testimony whereof we affix our signatures.

ALFRED BARTLETT SMITH.
CLIFFORD ROSS SMITH.
